[57] **CLAIM**

The ornamental design for a scoop body for a toy shovel, as shown and described.

DESCRIPTION

FIG. 1 is a perspective view the present scoop body for a toy shovel showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The handle portion of the toy shovel is illustrated in broken line in FIG. 1 for environmental purposes only, and it is not intended to form any part of the present design.
